(57) **CLAIM**

The ornamental design for a breast pump hose adapter as shown and described.

DESCRIPTION

FIG. 1 is a top front perspective view of a breast pump hose adapter according to the invention.

FIG. 2 is a bottom rear perspective view of the breast pump hose adapter of FIG. 1.

FIG. 3 is a front view of the breast pump hose adapter of FIG. 1.

FIG. 4 is a rear view of the breast pump hose adapter of FIG. 1.

FIG. 5 is a right side view of the breast pump hose adapter of FIG. 1.

FIG. 6 is a left side view of the breast pump hose adapter of FIG. 1.

FIG. 7 is a top view of the breast pump hose adapter of FIG. 1; and,

FIG. 8 is a bottom view of the breast pump hose adapter of FIG. 1.

The broken lines in the drawings illustrate portions of the breast pump hose adapter and form no part of the claimed design.

1 Claim, 5 Drawing Sheets
